ROCKET PRIMER

Filed April 6, 1944

UNITED STATES PATENT OFFICE

2,462,135

ROCKET PRIMER

Leslie A. Skinner, Washington, D. C., assignor to
the United States of America as represented by
the Secretary of War

Application April 6, 1944, Serial No. 529,763

3 Claims. (Cl. 102—70.2)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to rocket projectiles and more particularly to an electrical igniter carried by the rocket and adapted to ignite its propellant charge upon firing or launching. It is an object of this invention to provide an improved electrical igniter which is adapted to be inserted in the rear end of the rocket projectile and which is provided with electrical contact means which are contacted by electrical switches provided on the rocket gun or launcher. The rocket is launched by closing the electrical circuit, which includes the said contacts provided in the igniter, to a source of current. For the attainment of this and such other objects of invention as may appear or be pointed out herein I have shown one embodiment of my invention in the accompanying drawing, wherein:

Fig. 1 shows the rear portion of a rocket projectile with its rear nozzle mouth in section to reveal the improved igniter;

Fig. 2 is a longitudinal section through the improved igniter;

Fig. 3 shows the outer contact ring and

Fig. 4 shows the inner contact disc.

The igniter comprises a cup 10 preferably fabricated of plastic but which may be made of other material. Plastic cup 10 is internally threaded at its mouth to receive a circular closure plate 11 provided with an annular rim 12 which is externally threaded for screwing into the cup. Instead of the threads, other joining means may be used, such as a pressed fit between the mouth of cup 10 and rim 12 of closure plate 11. Plate 11, which likewise is preferably made of plastic, has inserted in its outer face an outer contact ring 13 and an inner centrally located contact disc 14. Contact ring 13 and contact disc 14, which are fabricated of brass or other suitable conducting metal, are preferably inserted in and made part of the plastic plate 11 during the molding operation. Two holes are then drilled through the closure plate 11; one drill hole 15, inclined to the longitudinal axis of igniter cup 10, passes through the outer contact ring 13, while the other drill hole 16 parallel to the longitudinal axis of the cup, passes through inner contact disc 14. The two lead wires of an electrical fired squib or primer 20 are then inserted in the two holes, squib wire 25 in ring hole 15 and squib wire 26 in disc hole 16, and soldered in place; the end of the wires are then cut off flush with the surfaces of

the ring and disc contacts. The plate 11, with squib 20 held by its soldered lead wires, is then screwed into cup 10, and the latter loaded with black gunpowder 17. For this purpose the bottom 5 of cup 10 has a large loading hole 18 which is closed after the loading operation by a disc 19 preferably made of cloth and conveniently held in place by shellac. The border surrounding loading hole 18 is coated with shellac as is the inside border of cloth disc 19; after the disc is positioned in place, a final coat of shellac is applied over the disc.

The edge of plate 11 is tapered in substantial conformity to the taper of the rocket nozzle 9, 15 and the igniter assembly, or rather the plate 11, is press fitted in the nozzle, with the cup 10 extending into the expansion nozzle 8 of the rocket projectile 7. A portion of the projecting or launching mechanism is shown in Fig. 1 and bears 20 the reference character 30. Launching tube 30 is provided with a pair of switch contacts pivoted at 31, one of the switches 33 being contactable with the outer ring 13 and the other of the switches 34 being contactable with the inner disc 14. The pair of switches are turned to out-of-contact position, shown in dot-and-dash lines in Fig. 1, preparatory to loading the rocket 7 in launching tube 30. After the rocket has been placed in the breech end of the launcher, the 25 pair of electrical switches 33 and 34 are turned to contact the respective contacts 13 and 14 of the igniter, this contact position of the switches being shown in solid lines in Fig. 1. The electrical switch mechanism of the launcher is implemented 30 with a tensile spring 32 arranged to either spring press the switches into contact with the ring and disc surfaces of the igniter, or to hold the switches in their out-of-contact position.

It should be observed that, by reason of the 40 center contact disc 14 and outer annular contact ring 13, the improved igniter may be placed in the launching tube without regard to angular co-ordination between the rocket and the launcher. With the switches 33 and 34 in contact with the 45 igniter, the rocket projectile is fired or launched by closing the circuit, which includes the squib 20, contact surfaces 13 and 14 and switch contacts 33 and 34, to a source of current (not shown).

The rocket propellant with which the combustion chamber of the rocket is charged is a double-base powder requiring a sustained pressure to ensure satisfactory ignition. The improved igniter, by reason of the action of the black powder (17, Fig. 2) with which it is charged, serves the added 55 function of building up within the combustion

chamber an initial pressure sufficient for the initial ignition and functioning of the propellant and to insure proper continued burning of the propellant.

I claim:

1. An electrical igniter adapted to be inserted in the nozzle opening of a rocket projectile and adapted to establish electrical contact with the pair of electrical switches provided in the rocket launcher, comprising, in combination, a plastic cup provided with internal threads at its mouth and with a centrally located hole in its bottom, a plastic circular plate provided with an annular flange externally threaded for screwing into the said threaded mouth of the cup, a cloth disc somewhat larger than the said cup hole and adapted to be shellac-adhered to the outside of the cup to close the said hole, an outer metal ring and an inner metal disc moulded in the said plastic plate with their exposed surfaces flush with the outer face of the plastic plate to furnish a pair of electrical contacts, the said plastic plate having a pair of drilled holes, one drill hole passing through the said outer ring and the other drill hole passing through the said inner disc, an electrically-fired primer positioned within the said plastic cup with its two lead wires soldered in the two said drilled holes, the edge of the said plastic plate being beveled to the taper of the said rocket nozzle and adapted to be press fitted in the nozzle, the said cup being received within the expansion nozzle of the rocket projectile with the said outer ring and inner disc positioned at the said rocket nozzle to be contacted by the said pair of electrical switches of the launcher irrespective of the angular position of either the electrical igniter or the rocket projectile.

2. An electrical igniter adapted to be inserted in the nozzle opening of a rocket projectile and adapted to establish electrical contact with the pair of electrical switches provided in the rocket launcher, comprising, in combination, a cup provided with internal threads at its mouth and with a centrally located hole in its bottom, a circular plate provided with an annular flange externally threaded for screwing into the said threaded mouth of the cup, a cloth disc somewhat larger than the said cup hole and adapted to be shellac-adhered to the outside of the cup to close the said hole, an outer metal ring and an inner metal disc held in the said plate with their exposed surfaces flush with the outer face of the plate to furnish

a pair of electrical contacts, the said plate having a pair of drilled holes, one drill hole passing through the said outer ring and the other drill hole passing through the said inner disc, an electrically-fired primer positioned within the said cup with its two lead wires soldered in the two said drilled holes, the edge of the said plate being beveled to the taper of the said rocket nozzle and adapted to be press fitted in the nozzle, the said cup being received within the expansion nozzle of the rocket projectile with the said outer ring and inner disc positioned at the said rocket nozzle to be contacted by the said pair of electrical switches of the launcher irrespective of the angular position of either the electrical igniter or the rocket projectile.

3. An igniter comprising a plate of electrical insulating material adapted to fit within and to close the nozzle opening of a rocket projectile, a contact ring and a contact disc carried by said plate on the side thereof which faces outwardly of the rocket when the plate is fitted within the nozzle opening of the rocket projectile, said disc being positioned within said ring and spaced therefrom, whereby two insulated electrical contacts are provided by said ring and disc, a container for explosive carried by the plate on the side thereof opposite the side which carries the said ring and disc; an electric squib in said container, one lead of said squib passing through said plate and connecting with said ring and the other lead of said squib passing through said plate and connecting with said disc; and a non-detonating explosive in said container about said squib.
